NONREFILLABLE BOTTLE

Frank A. Buono, Hackensack, N. J.

Application December 11, 1933, Serial No. 701,921

2 Claims. (Cl. 215—25)

This invention relates to bottle closures and particularly to an improved closure of the non-refillable type, the object being to provide an improved construction which is simple and yet effective.

Another object of the present invention is to provide a closure which is strong and which readily functions to permit liquid to flow from a container but acts to prevent the entrance of a liquid.

10 An additional object is to provide in a closure of the non-refillable type, means which will automatically close by gravity, with one portion positioned interiorly of the other and substantially independent thereof so as to prevent any unauthorized adjustment at any time.

In the accompanying drawing—

Figure 1 is a longitudinal vertical sectional view through the container formed with a discharge neck and a closure structure embodying the present invention;

20 Figure 2 is a view similar to the upper part of Figure 1, but showing the parts in substantially inverted position whereby the liquid in the container will readily flow therefrom;

25 Figure 3 is a view similar to Figure 1 but showing a slightly modified construction;

Figure 4 is a view similar to Figure 1 but showing another form of the invention.

30 Figure 5 is a view similar to Figure 4 but showing a further modified form of the invention.

Referring to the drawing by numerals, 1 indicates a container of any desired kind. As shown in the accompanying drawing the container 1 is a glass bottle and is formed with a neck 2 of a desired size. The neck 2 is of the usual structure now in common use on the market and is adapted at the upper end to receive a stopper 3 in the usual manner.

35 This stopper 3 is desirable so that none of the liquid contents of the bottle can pass out when being shipped or handled. However, when the contents are to be used the stopper 3 is removed and, if desired, may be thrown away or reinserted after first use. The neck 2, in addition to being of the usual form exterior, is provided internally with a special division or partition 5. The division or partition plate 4 is provided with an aperture 6 which is appreciably larger than the tubular member or shank 7 of the cap 8, which cap 40 is much larger than the aperture 6 but smaller than the bore of the neck 2 whereby it loosely fits in this bore and rests tightly against the upper surface of the partition 4. The tubular member 7 acts as a guiding member for the cap 8, and 45 also as a weight for holding the same normally

in the position shown in Figure 1, whereby the container 1 is maintained closed at that point. A plurality of springs 9 are carried by the lower end of the tubular member 7 and flare therefrom, the outer ends of these springs being adapted to strike the under surface of the division plate 4 when the bottle is inverted or substantially inverted as shown in Figure 2. Preferably the springs 9 are really resilient spurs extending from a central plate 10 and secured in any desired 5 manner to the tubular member 7. It will be understood that the tubular member 7 and the cap 8 may be made from metal, glass, porcelain or other material without departing from the spirit of the invention. The plate 10 is, however, preferably made from rust-proof steel or other desirable material which will best serve the purpose.

50 The division member 5 does not extend straight across the interior of the neck 2 as is the case with the plate 7, but extends upwardly and forms a cam which merges into a tubular extension 11 20 preferably smaller in diameter than the aperture 6. This tubular extension is provided with a beveled upper end forming a seat 12 against which the washer 13 presses when the parts are in closed 25 position. The washer 13 is arranged in a recess 14 in the cap 15, which cap is provided with inclined walls substantially parallel to the seat 12 but overlapping this seat for some appreciable distance, and then merging into a depending 30 apron 16 whereby there is provided a space between the apron 16 and the tubular extension 11. This provides a loose fit and one whereby the cap 35 may be properly centered so that the washer 13 may fit properly against the seal 12. To assist in properly seating the valve, to guide the same, and also to hold it always in position for proper actuation, there is provided a pin or rod 17 which is shown as being formed integrally with the cap 40 15, though it could be made separately and rigidly secured thereto. This pin or rod 17 is appreciably smaller than the bore of the tubular extension 11. It will thus be seen that the cap and all parts associated therewith are made of the proper size to loosely fit the tubular extension 45 11, except those parts which fit tightly against the seat 12.

55 When the bottle or container 1 is in an upright position as shown in Figure 1, the cap 15 will be closed and also cap 8, thus preventing entrance of any liquid or other matter. However, when it is desired to remove any of the liquid from the container 1, the same is inverted or almost inverted as shown in Figure 2, whereupon the cap 8 will move down by gravity until the springs 9 55

stop such movement. This will leave a passageway around springs 9 and through aperture 6. The cap 15 will also fall down by gravity and by the force of the outpouring liquid, until it 5 moves to the position shown in Figure 2 against the disc 10. It will remain centered as shown in Figure 2, or it may drop to one side, but the pin 17 cannot move away from the tubular extension 11. When the parts are in the 10 position shown in Figure 2 liquid may freely flow out of the container. If desired a small quantity may be discharged or the entire contents of the container. After a desired amount has been discharged it is only necessary to move the 15 container to an upright position and the parts will again quickly assume the position shown in Figure 1. When in this position the two aligned openings are closed and substantially sealed, thus protecting the liquid in the container and preventing the entrance of any diluting liquid. 20

Figure 3 shows a slightly modified structure. In this form of the invention the same reference numerals will be used as in the preferred form, except that which refer to the modified parts. 25 In this form there is provided an interior annular thickness 18 instead of a cone-shaped division plate such as member 5. This annular thickness or interior ring is provided with tapering valve seat 19 adapted to receive a valve member 20 which is cone-shaped. This valve member is preferably covered with rubber or other material 21 which is slightly resilient whereby when the cone is seated a tight connection is produced. Aside from these details the structure is identical 30 with that shown in Figure 1 and functions in the same manner.

In Figure 4 a further form of the invention is presented, the structure being similar to that shown in Figure 1 except for the upper part. Instead of having a cap 8 there is provided a cap 8' having a tubular member 7' which is provided with a bore 22 extending entirely therethrough. This bore carries pistons 23 and 24 having piston rods 25 and 26. When the tubular member 7' 40 is placed in position the piston rods are forced within the passageway 22 against the action of spring 27 and is held in this position by either the fingers or any other suitable instrument until the rods 25 and 26 have passed through the opening 6' which is larger in comparison than this opening 6. As soon as the piston rods are passed through this opening they are released and are immediately forced outwardly radially by the spring 27 until they slightly contact with or almost contact with the interior walls of the neck 2. Little or no friction is provided between the 45 piston rods 25 and 26 and the neck 2. This is necessary in order to permit the cap 8' to readily move back and forth. However, these rods prevent the cap from being removed. Aside from these structures the device is identical with that shown in Figure 1 and the same reference numerals will be used except in the modified parts. 50

In Figure 5 a further modified form of the invention is disclosed wherein the head or cap 8'' rests on the washer 28 so as to provide a tight fit when the device is closed. The tubular por-

tion 29, however, is quite different from that shown in Figures 1 and 4, in that it is provided with a notch 30 which merges into a slot 31 whereby the bar 32 may be positioned as shown in Figure 5, or may be swung at right angles to that position so as to be positioned substantially as indicated by the dotted lines. The piece 32 is provided with a single pin 33 extending therethrough, though if desired this pin could be made integral with the piece 32 so as to present integral trunnions extending therefrom. This pin is fitted into a slot 34, it being understood that there will be two slots 34, because the structure shown in Figure 5 is in section. A spring 35 is wound around the pin 33 and has one end resting at 37 10 against the bar 32. This gives the bar a continuous tendency to press against the shoulder 38 at the end of slot 31. The parts are normally in position as shown in Figure 5 when the device is in operative position. Before the stopper has 15 been inserted the bar 32 is turned to the dotted position, and then the bar, tubular member 29 and associated parts are inserted through the opening 6. As soon as the bar 32 passes through the opening, it will immediately and quickly move to 20 the position shown in Figure 5. When in this position the stopper cannot be removed. Along with this stopper, a cap similar to cap 15, shown in Figure 1, is used as an inner stopper, the same as is true of the structure shown in Figure 4. 25

I claim:

1. A device of the character described including a container having a discharge stem formed with a pair of partitions, one partition being flat and apertured and the other partition being cone-shaped and merging into a tubular extension having a valve seat at the upper end, a valve member for the flat partition, said valve member having means for permitting reciprocation but preventing removal of the valve member from the partition, an independent valve member normally spaced from the first mentioned valve member for the second partition formed with valve surfaces adapted to engage the valve surfaces on said tubular extension, and a pin extending from the last mentioned valve through said tubular extension, said pin being sufficiently long to have a portion remain in said tubular extension when the container is inverted, whereby it acts to prevent complete removal of the last mentioned valve from its seat, said last mentioned valve when said container is inverted moving down to a position in contact with the first mentioned valve. 40

2. A device of the character described including a container having a discharge neck formed with a pair of division members, one division member having a centrally positioned bore and a valve member loosely fitted therein and positioned to seal the same when the container is in an upright position, the other partition member having a tubular extension having a beveled valve seat at the upper end and a cap fitting over said tubular extension, said cap having an annular inner recess, and a gasket fitted in said recess, said gasket being located to fit against said valve seat when said valve is closed. 45
